UNITED STATES PATENT OFFICE.

LLOYD H. BARDACH, OF CHICAGO, ILLINOIS, ASSIGNOR, BY MESNE ASSIGNMENTS, TO GOLD DUST CORPORATION, OF NEW YORK, N. Y., A CORPORATION OF NEW JERSEY.

GLASS-CLEANING APPLICATOR.

Application filed April 17, 1925. Serial No. 23,869.

This invention relates to a fluid applicator for glass or the like and concerns itself with a flexible nipple or the like which is adapted for forming the closure for a fluid container and which is so constructed that in use the fluid feeding apertures in the nipple will not tend to close or become clogged so that a sufficient and steady feed of the cleansing fluid may be maintained.

10 The invention comprises the novel structure and combinations hereinafter described and more particularly pointed out and defined in the appended claims.

In the accompanying drawings, which illustrate a preferred embodiment of this invention and in which similar reference numerals refer to similar features in the different views,

20 Figure 1 is an elevational view of a container closed by an applicator involving this invention;

Figure 2 is an enlarged top plan view of the applicator;

25 Figure 3 is a sectional view upon the line III—III of Figure 2; and

Figure 4 is a sectional view upon the line IV—IV of Figure 2.

Referring to the drawings, there is shown a container in the form of a bottle 1 adapted to contain glass cleansing fluid. An applicator 2 is adapted to be attached over the mouth of the container for exuding the cleansing fluid within the container.

30 This applicator consists of a hollow flexible member open at its lower end and closed at its upper end except for the fluid feeding apertures 3. The applicator preferably consists of some such material as rubber. Its upper end is preferably of rounded 35 form and is provided with a plurality of upwardly projecting segmental arcuate ribs 4 which, in the present instance, lie in the same circle. It will be noted that the fluid feeding apertures 3 are within the confines

of the segment 4. This segment 4 absorbs 45 the thrust of the applicator and prevents the fluid feeding apertures from being closed or clogged.

The lower end of the applicator is provided with an annular attaching flange 5 50 which is adapted for engagement by the rim of a cap 6 threaded upon the neck of the bottle.

It will be appreciated that in applying cleansing fluid to a glass surface, it is necessary to rub the top or nose of the applicator over the same. Such a rubbing action would interfere with the flow of fluid if it were not for the projecting segments 4 which absorb the thrust and wear and space 60 the fluid feeding openings a trifle from the surface of the glass.

I am aware that changes may be made and details of construction may be varied without departing from the principles of 65 this invention, and I therefore do not purpose limiting the patent granted hereon, otherwise than necessitated by the scope of the claims.

I claim as my invention:

1. In an applicator of the class described, a hollow flexible member open at its lower end and provided with a rounded top having upwardly extending segmental arcuate ribs, and fluid feeding apertures within the 75 confines of said ribs.

2. An applicator, comprising a flexible member having a lower annular flange adapted for attachment over the mouth of a container and having an upper rounded 80 surface provided with spaced upwardly extending segmental arcuate ribs, and fluid feeding apertures within the confines of said ribs.

In testimony whereof I have hereunto 85 subscribed my name.

LLOYD H. BARDACH.
